UNITED STATES PATENT OFFICE.

WILLIAM HENRY ARMSTRONG, OF NEW ORLEANS, LOUISIANA.

POISON-BOTTLE CAP.

1,423,174.

Specification of Letters Patent.

Patented July 18, 1922.

Application filed July 22, 1920. Serial No. 393,036.

To all whom it may concern:

Be it known that I, WILLIAM H. ARMSTRONG, a citizen of the United States, residing at New Orleans, in the parish of Orleans and State of Louisiana, have invented a new and useful Poison-Bottle Cap, of which the following is a specification.

This invention relates to bottle caps and it includes the novel features hereinafter described and claimed.

When stored in small quantities, poison fluids are usually retained in small bottles closed by corks or stoppers, and these bottles are frequently placed on shelves or in receptacles with other bottles containing medicines. Numerous instances are known where the bottles have become mixed or misplaced and as a consequence persons have taken or administered fluid from a poison bottle when it was the intention to use the fluid from a medicine bottle. The consequences of such mistakes have been attended by results more or less serious and in each instance causing physical suffering and personal inconveniences, all of which might have been avoided if the safeguards offered by this invention had been utilized.

An object is to provide a cap adapted to be removably applied to the neck of a bottle and which extends over the stopper or cork, and which is provided with tentacles having outstanding spurs adapted to serve as a warning signal to caution one who handles the bottle to exercise care as to how the contents of the bottle are used. This caution signal is manifest in the dark as well as in the light, consequently its use is an assurance that the mistakes mentioned cannot again be made.

40 In the accompanying drawing:

Figure 1 is a side view of a bottle showing the cap applied.

Figure 2 is a similar view showing the cap in section, and

45 Figure 3 is a conventionalized plan view of the cap.

As illustrated in the accompanying drawing, bottle 1 is of conventional form and is closed by a cork 2. The form of the cork is immaterial and any style or pattern of cork or stopper may be used.

The cap is formed from a blank of sheet metal, celluloid or any other suitable material and includes a central disk shaped

any suitable legends to indicate the contents of the bottle or which may serve advertising purposes. The cap also includes radially disposed tentacles 4 which extend outwardly from the body 3 and which are provided at intervals along their lengths with stuck-up spurs 5. The tentacles are preferably pointed at their outer ends as at 6, and one of the tentacles is provided with an opening 7 through which the link of a chain, or other securing device, may be passed for retaining the cap upon the neck of the bottle.

When the blank is formed in its final shape it is substantially of tentiform configuration, as best illustrated in Figures 1 and 2 of the drawing. When so formed the innermost spurs 5 stand up about the edge of the body portion 3 and the other spurs stand out from the tentacles.

When the cap is applied the body portion 3 lies over the top of the cork or stopper and the tentacles extend along the cork and neck of the bottle and engage around the head and the mouth of the bottle, as best indicated in Figure 2. By reason of the fact that the tentacles possess certain resiliency and pliability they may be readily sprung over the head and the mouth of the bottle when the device is applied or removed, and by reason of these characteristics the end portions of the tentacles grasp the neck of the bottle between them, thus securely holding the cap in position upon the bottle.

In the present instance the means for connecting the cap with the bottle neck consists of a chain 8 having one of its terminal links passing through the opening 7 and its other terminal link connecting with a band 9 which surrounds the neck of the bottle and fits snugly thereon.

Hence it will be seen that when the bottle is closed and the cap is applied, a person who grasps the bottle and attempts to remove the cork or stopper will bring his hand in contact with the spurs, and as the spurs are sharp they will serve as a signal and warn the person that the bottle contains a fluid which must be used with care.

After the bottle has been used, and in the event that the cork or stopper is replaced, and an attempt should be made to place the bottle upon a shelf or other support without applying the cap to the stop-

per or cork, some inconvenience will be experienced for the reason that the cap will be hanging or dangling along the side of the bottle; therefore when the bottle is replaced upon the support the user is warned that the hanging cap should be placed over the cork or stopper before leaving the bottle upon its support.

From the foregoing description, taken 10 in conjunction with the accompanying drawing, it will be seen that a poison bottle cap of simple and durable structure is provided and that the same will warn those who use or handle the bottle and caution 15 them to observe precautions to prevent the improper use of the contents of the bottle or exposure to accidental use.

Having described the invention, what is claimed is:—

20 1. The combination with a bottle having a closure means, of an indicator of the class described comprising bottle gripping means and an intermediate portion engaging with said closure means to determine the extension 25 of the gripping means upon the bottle and preventing removal of said closure without displacement of the indicator.

2. In combination with a bottle having a stopper, an indicator comprising a body 30 portion in engagement with the top of said stopper and co-acting to retain the latter in the mouth of the bottle, and bottle gripping tentacles radiating therefrom.

3. The combination with a bottle having 35 a stopper, of bottle gripping means formed with projections surrounding the top and sides of the stopper and adapted to act as a warning means, and an intermediate horizontal portion engaging the top of said 40 stopper to prevent accidental displacement thereof.

4. An indicator for poison bottles or containers, comprising a body, and jaw members adapted to be disposed upon the mouth 45 of the bottle or container, said jaw members being curved inwardly so as to cooperate with said mouth to tend to draw the

indicator tightly over the same when engaged therewith.

5. An indicator for poison bottles or containers having closure means, comprising a body extending over the closure means, and jaw members projecting therefrom and arranged circumferentially thereof, the entrance to said jaw members being of smaller 55 diameter than the same dimension at an intermediate point whereby upon engagement with the mouth of the bottle or container the jaw members are caused to grip and slide downwardly over said mouth to bring said 60 body into engagement with the closure means.

6. A poison indicator for bottles and the like, comprising a bottle attachment formed from sheet material, said attachment comprising a central disc stopper engaging portion and a series of radiating arms or tentacles, said arms or tentacles being bendable to angular position with respect to the disc portion to form gripping means engaging 70 with the bottle.

7. A poison indicator for bottles and the like, comprising a bottle attachment formed from sheet material, said attachment comprising a body portion and a series of radiating arms or tentacles, said arms or tentacles being bendable to form inwardly inclined gripping means cooperating with the bottle mouth tending to draw the attachment tightly thereover and having projections stamped therefrom and constituting 80 indicator means.

8. A poison indicator for bottles and the like, comprising a bottle attachment formed from sheet material, said attachment comprising a central body portion and a series of radiating jaws having stamped therethrough a series of sharp projections projecting outwardly at right angles to said gripping means for a warning or content indicating means.

In testimony whereof I affix my signature.

WILLIAM HENRY ARMSTRONG.
